STRIP TAKE-UP BLOCK

Frank E. Robinson, Shaker Heights, Ohio

Application August 29, 1939, Serial No. 292,514

2 Claims. (Cl. 242—72)

This invention relates to strip take-up blocks in general, but it is particularly concerned with a take-up block adapted to receive and coil cold rolled strip steel.

5 A specific example of the invention is illustrated in the accompanying drawings, in which:

Figure 1 is a longitudinal sectional elevation taken from line I—I of Figure 2; and

10 Figure 2 is a sectional elevation taken from line II—II of Figure 1.

More specifically, these drawings show a cold rolled steel strip take-up block comprising an end plate 1 from which a cylinder 2 extends, this cylinder 2 rotatively journaling a cylinder 3 by way 15 of bearing liners 4. A row of radially projecting cams 5 extends longitudinally of the cylinder 3, these cams being welded to this cylinder. Rotation of the cylinder 3 may be effected by operation of a handwheel 6 fixed to the end of this 20 cylinder remote from the plate 1.

A cylinder 7 extends from the plate 1 concentrically outside of the others, this cylinder 7 having two longitudinally hinged radially swinging segments 8 and 9, the adjacent sides of these segments having interengaging edges 10 and 11, the edge 10 being shaped to ride under the edge 11 upon inward swinging of the segments 8 and 9. As shown by the drawings, the edges are oppositely beveled so as to accomplish this result. The 30 segment 8 mounts a row of rollers 12 extending longitudinally thereof adjacent its swinging portion, or, in other words, the edge 10, these rollers interengaging with the cams 5 upon rotation of the cylinder 3 by the handwheel 6.

35 Rotation of this cylinder 3 is limited by spaced stops 13 fixed to this cylinder, these stops engaging an abutment 14 fixed to the inside of the cylinder 7. It follows that rotation of the cylinder 3 within the limits defined by the stops 13 effects collapse or replacement of the segments 8 and 9, the collapse of these segments permitting a tight strip coil to be removed from the cylinder 7, it being understood that this cylinder receives the strip, it having for this purpose a longitudinal 45 slot 15 in which an end of the strip may be engaged at the start of coiling.

It is desirable that the outside of the cylinder 7 be as smooth and continuous as is possible and to attain this end the edges 10 and 11 are made to 50 closely fit so that when the cams 5 work against the rollers 12 to build the cylinder 7, the outsides of the segments 8 and 9 provide a substantially smooth and continuous surface at the junctions of their swinging sides. Furthermore, hinging of 55 these segments 8 and 9 is effected by piano hinges

16 and 17 having exteriors conforming to the contour of the cylinder 7, the hinged sides of the segments 8 and 9 having edges 18 and 19 cooperating with the edges 20 and 21 of the remainder of the cylinder 7 to form a smooth, substantially continuous, cylindrical surface for receiving the strip coiled on the cylinder 7. This effect is obtained by proper contouring of the edges 18, 19, 20 and 21. By means of the arrangement just described, the first wrap of strip about the cylinder 7 retains its finish and flatness.

I claim:

1. A strip take-up block comprising an end plate, a first cylinder extending from said plate, a second cylinder rotatively journalled on said first cylinder, a row of radially projecting cams extending longitudinally of said second cylinder, a third cylinder extending from said plate concentrically outside of the others, said third cylinder having two longitudinally hinged, radially swinging segments with adjacent sides having interengaging edges of which one is shaped to ride under the other upon inward swinging of said segments, the one of said segments having said edge riding under the edge of the other having a row of roller elements extending longitudinally thereof adjacent its swinging portion for interengagement with said cams, and a handwheel fixed to the end of said second cylinder opposite said plate.

2. A strip take-up block comprising an end plate, a first cylinder extending from said plate, a second cylinder rotatively journalled on said first cylinder, a row of radially projecting cams extending longitudinally of said second cylinder, a third cylinder extending from said plate concentrically outside of the others, said third cylinder having two longitudinally hinged, radially swinging segments with adjacent sides having interengaging edges of which one is shaped to ride under the other upon inward swinging of said segments, the one of said segments having said edge riding under the edge of the other having a row of roller elements extending longitudinally thereof adjacent its swinging portion for interengagement with said cams, and a handwheel fixed to the end of said second cylinder opposite said plate, the sides of said segments having edges cooperating with each other and with the edges of the remainder of the cylinder to form a smooth, substantially continuous cylindrical surface for receiving strip coiled thereon.
